Charles D. Gooding.

UNITED STATES PATENT OFFICE.

BENJAMIN A. POND, OF BOSTON, MASSACHUSETTS.

INSULATOR.

No. 918,905.

Specification of Letters Patent.

Patented April 26, 1909.

Application filed September 5, 1908. Serial No. 451,768.

To all whom it may concern:

Be it known that I, BENJAMIN A. POND, a citizen of the United States, residing at Boston, in the county of Suffolk and State 5 of Massachusetts, have invented new and useful Improvements in Insulators, of which the following is a specification.

This invention relates to improvements in insulating devices, and the object is to 10 provide an insulating device into which a wire may be quickly and easily introduced without cutting the same to get it into the insulator and which shall permit the wire when in place to slide longitudinally there- 15 through.

The object is further to provide an insulating device of the character referred to which shall effectually prevent grounding of the current through the support on which 20 the device is mounted, the device of my invention being particularly adapted for use as a tree insulator and when in use as such the swaying of the tree is not apt to break the wire for the reason that the wire is free 25 to slide longitudinally therethrough.

The invention consists in the combination and arrangement of parts set forth in the following specification and particularly pointed out in the appended claims.

30 Referring to the drawing: Figure 1 is an elevation of an insulator embodying my invention, the same being closed as it appears when in use. Fig. 2 is an elevation of the insulator shown in its open position, 35 the upper half of the insulating bushing being removed for the introduction of the wire. Fig. 3 is a sectional elevation taken on line 3—3 of Fig. 1, looking toward the left.

40 Like numerals refer to like parts throughout the several views of the drawing.

In the drawing, 5 is a holder comprising two parts 6 and 7 provided, respectively, with ears 8 and 9 through which a pivotal 45 pin 10 extends, said parts constituting a ring which is located in an annular groove 11 formed in an insulating bushing 12, said bushing being made up of two parts 13, 13 and said bushing having a central hole 14 50 adapted to receive a wire such as the wires in use in the streets for the transmission of electricity for electric lighting and power purposes. The hole 14 is preferably rounded at both ends so as not to chafe the insulation 55 on the wire. The wire, which is not shown, is placed in the lower half of the bushing 12

when the parts are in the position shown in Fig. 2, the upper half of the bushing is then brought in place above the lower half and there is preferably placed between the abutting faces of both parts an element 15 which preferably consists of a suitable cement which permanently unites the parts of the bushing so that they constitute an unbroken ring, thus preventing any grounding which 60 might possibly take place were it not for the provision of this element. When the two parts of the bushing are thus united, the upper part 6 of the holder is then swung down into place into the position shown in Fig. 1 and secured in such position by means 65 of a bolt 16 passing through the parts 6 and 7 and having screw threaded engagement with a nut 17 by which said parts are securely united, thereby holding the insulating bushing 12 in place.

Without departing from the spirit of my invention, the element 15 might consist of soft gutta-percha or rubber of the proper thickness so that the same would be compressed by tightening the nut 17 on the bolt 16. It will also be understood that if desired instead of providing the insulating bushing with the groove, that the holder may be provided with a groove adapted to receive a corresponding projection on the bushing.

To secure the holder to a support, such, for example, as a tree, I provide any suitable means, as for example, a screw 18 which in this instance is formed integral with the part 7, said screw being adapted to be screwed into the tree.

One of the great advantages secured by the device of my invention as compared with other insulating devices is that the wire may 95 be placed therein without cutting owing to the fact that the bushing is made in two parts and yet the device when assembled forms as perfect an insulator as if the bushing were a solid ring owing to the provision of the 100 element 15. Another great advantage secured by the use of my device is that the wire is free to slide longitudinally through the hole 14 so that the wire is not subjected to such strain as in the case of insulators in 105 which the wire is rigidly secured thereto and, therefore, in the use of my device the swaying of the tree to which it may be attached is not apt to break the wire as is the case in the other mentioned devices.

110 The insulating bushing 12 may be formed of any suitable material, but I prefer to em-

ploy for this purpose glass, while the holder is, of course, preferably formed of metal.

Having thus described my invention, what I claim and desire by Letters Patent to secure is:

1. An insulating device having in combination, a holder, a bushing formed of insulating material in two parts held by said holder, and an element located between the abutting surfaces of said parts.
2. An insulating device, having in combination, a holder, and a bushing formed of insulating material in two parts held by said holder, the abutting surfaces of said parts being cemented together, whereby said bushing constitutes a continuous unbroken ring.
3. An insulating device, having in combination, a holder comprising two relatively movable parts, a bushing formed of insulating material formed in two parts held by said holder, an element located between the abutting surfaces of said parts of said bushing, and means to impart a relative movement to said parts of said bushing, whereby said element is compressed therebetween.
4. An insulating device, having in combination, a holder, a bushing formed of insulating material formed in two parts held by said holder, an element located between the abut-

ting surfaces of said parts, and means to impart a relative movement to said parts, whereby said element is compressed therebetween.

5. An insulating device, having in combination, a holder comprising two relatively movable parts, a bushing formed of insulating material in two parts held by said holder, an element located between the abutting surfaces of said parts of said bushing, and means to impart a relative movement to said parts of said holder, said parts of said holder in turn imparting a relative movement to said parts of said bushing, whereby said element is compressed therebetween.

6. An insulating device, having in combination, a holder, a bushing formed of insulating material in two parts held by said holder, an element located between the abutting surfaces of said parts, and means to secure said holder to a support.

In testimony whereof I have hereunto set my hand in presence of two subscribing witnesses.

BENJAMIN A. POND.
